UNITED STATES PATENT OFFICE

HENRY FREDERIC EASTER, OF HAYDEN, ARIZONA, ASSIGNOR TO AMERICAN SMELTING AND REFINING COMPANY, OF NEW YORK, N. Y., A CORPORATION OF NEW JERSEY

FURNACE COOLING BY STEAM

Application filed March 9, 1928. Serial No. 260,446.

The invention relates in general to the art of metallurgy and more particularly to a method of and apparatus for cooling a metallurgical furnace and preventing scorification 5 of the brickwork by the contents of the furnace.

According to the invention saturated boiler steam at boiler pressure may be used as the general cooling medium for cooling a metallurgical furnace. The furnace may be a reverberatory furnace and the steam may be conveniently obtained from the waste heat boiler of the furnace. The furnace may have suitable cooling devices located at different 15 points such as cooling jackets for the side walls or arch, cooled charge holes in the side walls or in the arch, etc. These cooling devices have conduits associated therewith for the cooling medium and the live saturated 20 steam is led to these conduits. The cooling of the furnace parts superheats the steam and this superheated steam may be led to any point where it can be used, such as the oil burners used for supplying the heat to the 25 furnace or directly to the inside surfaces of the furnace to protect the brickwork.

According to the invention the saturated steam may also be led directly to the inside of the furnace. Pipes containing this steam 30 may be led through the furnace wall to the inner face thereof where the steam may form a coating or film on the furnace wall. The action of this steam will vary with the kind of furnace and the kind of charge. In some 35 cases it may provide an inert film to prevent chemical action between the charge and the brickwork and in other cases the steam may combine with the charge to form strengthening accretions on the brickwork to protect 40 it from the scorifying action of the furnace charge.

The invention also consists in certain new and original features of construction and combinations of parts hereinafter set forth 45 and claimed.

Although the novel features which are believed to be characteristic of this invention will be particularly pointed out in the claims appended hereto, the invention itself, as to its objects and advantages, the mode of its op-

eration and the manner of its organization may be better understood by referring to the following description taken in connection with the accompanying drawings forming a part thereof, in which

Figure 1 is a diagrammatic view of one form of metallurgical furnace illustrating diagrammatically how the invention may be applied thereto.

Figure 2 is an enlarged section illustrating the action of the directly applied steam.

Like reference characters denote like parts in the several figures of the drawings.

In the following description and in the claims parts will be identified by specific 65 means for convenience, but they are intended to be as generic in their application to similar parts as the art will permit.

Referring now to the drawing, a form of reverberatory furnace is shown to illustrate 70 the principle of the invention. It will be understood that the illustration is purely diagrammatic and that the invention may be applied to other kinds of metallurgical furnaces which are capable of utilizing the principles of the invention.

The furnace as shown comprises the reverberatory hearth portion 1 having at one end oil burners 2 for supplying the necessary 80 heat. Between the other end of the hearth 1 and the flue 3 a waste heat boiler 4 is provided.

The furnace roof or arch 5 is shown provided with charge holes 6 which have cooling conduits 7. The furnace is also provided with cooling blocks 8 forming a cooling jacket for the side walls 9. It will be understood that as many cooled charge openings 6 will be provided in each case as is necessary and they will be placed in the arch or in the side walls 85 as desired and that the cooling blocks 8 may be placed at any point, depending upon the construction of the particular furnace.

In the drawings a saturated steam main 12 is shown leading from the waste heat boiler 4 90 and conveying live steam at boiler pressure which may be in the neighborhood of 150 to 200 pounds.

This steam main 12 leads to different parts 100 of the plant where the steam is needed and is

shown provided with branch conduits 13 leading to the various cooling blocks 8 and charge holes 6 for cooling these parts. Leading from the cooling blocks and charge holes 5 are branch conduits 14 leading back to another main 15, which is the superheated steam main. This main 15 may be led to any other part of the plant where superheated steam can be used. A branch 16 is shown extending to 10 the oil burner 2 from both the saturated steam main 12 and the superheated steam main 15. Also connected to the oil burner is a source of fuel oil and a source of compressed air.

Connected also to the saturated steam main 15 12 are branches 17 leading directly to the interior of the furnace and ending substantially flush with the inner face of the roof 5. These branches may also receive steam from the superheated main 15. It will be seen that these branches 17 may be used to convey either superheated or saturated steam directly 20 inside the furnace to form protective coatings upon the roof or on the side walls of the furnace, depending on the position and number of branch pipes. Valves 18 are provided in the several branches for controlling the steam flow.

In operation it will be understood that saturated steam, which is conveyed to the 20 cooling blocks and charge openings, is superheated by its cooling action, and the superheated steam is used to form the protective coating on the inside of the furnace, to improve the action of the oil burners, and for 25 other purposes, if desired.

The steam passing thru the branch pipes 17 which lead directly to the interior of the furnace form protective coatings on inside walls, the actions depending upon the kind of furnace and the material of the charge. In some 30 cases the steam may act merely as an inert gas to protect the brickwork from scorification due to the furnace charge. In other cases the dust or other material of the charge or 45 other contents of the furnace may combine chemically with the steam and form a precipitate which is deposited on the brickwork forming a strengthening accretion which protects the brickwork from the scorifying action.

Thus it will be seen that a method of cooling and protecting a metallurgical furnace has been provided which is inexpensive and efficient. Metallurgical furnaces are usually 50 provided with waste heat boilers so that steam is easily obtainable. The cooling action of boiler steam is more efficient than that of water and there is no danger of explosion 55 from accidental leaks. Furthermore, the utilization of steam directly inside of the furnace, forming a coating on the furnace walls, protects the brickwork from scorification and aids materially in increasing the life of the 60 furnace. Also the superheated steam ob-

tained from the cooling action may be used to improve the efficiency of the oil burners.

What is claimed is:

1. The method of protecting the inside wall 70 of a metallurgical furnace from the scorifying action of the contents of said furnace which comprises forming a coating of steam on said inside wall, without substantially changing the normal operating atmosphere throughout the body of the furnace.

2. The method of protecting the roof of a reverberatory furnace from the fluxing action 75 of the charge which comprises coating the interior of said roof with superheated steam, without substantially changing the normal operating atmosphere throughout the body of the furnace.

3. The method of protecting the inside wall 80 of a reverberatory furnace from the attacking action of the charge which comprises coating the interior of said wall with steam, without substantially changing the normal operating atmosphere throughout the body of the furnace.

4. The method of protecting the interior 85 of a wall of a metallurgical furnace from the fluxing action of the contents of said furnace which comprises coating a film of steam on said wall, reacting said steam and part of said contents and depositing the compound 90 formed on said wall to form a protecting accretion.

5. In combination, a source of saturated steam at boiler pressure, a metallurgical furnace having a cooling conduit associated with 100 the wall thereof, means for passing steam from said source thru said conduit to cool said wall and to superheat the steam, and means for passing said superheated steam directly to the interior of said furnace to form 105 a coating on the inner wall thereof.

6. In combination, a source of saturated steam at boiler pressure, a metallurgical furnace, a cooling conduit in a wall of said furnace, means for passing steam from said 110 source thru said cooling conduit and then directly to the interior of said furnace at the inner surface of the wall thereof.

7. In combination, a source of steam, a metallurgical furnace, a cooling conduit in a 115 wall of said furnace, and means for passing steam from said source thru said cooling conduit and then directly to the inside of said furnace.

In testimony whereof I have hereunto set 120 my hand.

HENRY FREDERIC EASTER.
